UNITED STATES PATENT OFFICE.

ALBIN DANIELSON, OF CHICAGO, ILLINOIS.

DOOR-CHECK.

995,665.

Specification of Letters Patent. Patented June 20, 1911.

Application filed May 18, 1910. Serial No. 561,987.

To all whom it may concern:

Be it known that I, ALBIN DANIELSON, a citizen of the United States, residing at Chicago, in the county of Cook and State of Illinois, have invented a new and useful Improvement in Door-Checks, of which the following is a specification.

My invention relates particularly to door-checks adapted for use in connection with spring-closed screen doors, although the invention may be used in other analogous situations.

My primary object is to provide a door-check of the character indicated of simple construction and improved operation.

The invention is illustrated in its preferred embodiment in the accompanying drawing in which—

Figure 1 represents a broken plan sectional view of a door and door-jamb equipped with my improved check, the dotted lines showing the door in the open position; Fig. 2, a broken elevational view of the same; Fig. 3, a broken sectional view showing the cylinder and plunger construction; Fig. 4, a view of a spring employed in connection with the cup or packing of the plunger; and Fig. 5, a view of a spring employed in connection with a pivoted arm which is connected with the outer end of the plunger.

In the illustration given, A represents a door-jamb; B a door connected therewith by spring-hinges 1; and C, my improved door-check. Any suitable hinges and spring device for closing the door may be employed. In the illustration given, an ordinary spring-hinge 1 is shown.

The device C preferably comprises a cylinder 2 attached to one leaf of a hinge 3 which is applied to the door; a plunger 4 movable in said cylinder; a bracket 5 applied to the door-jamb; an arm 6 pivotally connected at one end to said bracket and at the other end to the outer end of the plunger 4; and a coil-spring 7 having one end attached to the bracket 5 and the other end adapted to bear on the arm 6, said spring tending to maintain the arm 6 in contact with a wall or stop 8 for the bracket 5.

The hinge 3 has one leaf 9 adapted to be attached to the door, and another leaf 10 to which the cylinder 2 is attached at one end. Said cylinder 2 has a base-end 11 secured by rivets 12 to the leaf 10, and said cylinder-end 11 is provided with a central per-

foration which receives the end of a small cylinder or casing 13 which extends through a perforation 14 with which the leaf 10 is provided. The cylinder 13 has its inner end in free communication with the cylinder 2, and is provided with a closed outer end 15 having a passage 16 guarded by a ball-valve 17. The cylinder 13 also has a lateral port 18 guarded by the point of a screw 19 which has threaded connection with one wall of the cylinder 13, said screw thus serving as an adjustable valve. The ball 17 seats outwardly and is adapted to pull away from the port 18 to admit air freely while the door is being opened. During the operation of closing the door, the valve 17 is forced to its set position, and the escape of air is then through the port 18, which is regulable.

The plunger 4 has its inner end provided with a head carrying a flexible cup or bushing 20 which may be formed of leather, the flange of said cup-shaped member contacting with the inner wall of the cylinder 2. Within the flange of the cup-shaped member 20 is located a resilient split-ring, or circular spring, 21 whose function is to maintain the flange of the member 20 in close contact with the inner wall of the cylinder 2. Thus passage of air and dust past the bushing is prevented, a close joint being always maintained, so that when the air escapes from the cylinder 2 during the operation of closing the door, the escape must be through the cylinder 13 and port 18 thereof. Not only is a close joint maintained between the piston and cylinder 2, providing for a certainty of resistance in operation, but injury to the cup-shaped member, or packing, 20 is avoided, since the member 20 will not be dried out and otherwise injured by the passage of air and grit between it and the cylinder.

The bar, or arm, 6 is provided with a perforation 22, which receives a laterally turned end 23 of the plunger 4, thus providing a pivotal connection. The bracket 5 has a base-portion 24 which is secured to the door-jamb and has an outwardly projecting arm, 25 which is formed to support a pivot 26 with which the adjacent end of the arm 6 is connected, and is also formed to provide the wall, or stop, 8 against which the arm 6 is normally held by the spring 7. As shown, the spring 7 has a coiled portion supported by the pivot 26, and has a short

arm 27 secured to the base-portion 24 of the bracket and a long arm 28 which has its extremity bent to engage the link or arm 6.

The operation will be readily understood.

- 5 When the door is swung from the position shown in full lines in Fig. 1 to the position shown in dotted lines, the spring 7 resists to some extent the tendency of the arm or link 6 to swing on the pivot 26, and the 10 plunger 4 is thrown outwardly. During the opening of the door, however, the spring 7 yields, allowing the arm 6 to turn about the pivot 26, and finally the plunger 4 is withdrawn from the cylinder 2 the full length of 15 the stroke, a spring 4^a which surrounds the plunger and extends short of the free end of the cylinder serving to cushion the piston in its final outward movement. When the door is released, the usual spring with which 20 it is provided closes the door, the first closing action being aided by the spring 7, so that a rapid closing movement results during the first part of the closing operation, and thereafter the piston completes its 25 movement, expelling the air with less force through the port 18 so that slamming of the door is avoided. It should be added that in the operation of opening the door the check-valve 17 opens to admit air freely 30 to the cylinder 2, so that no resistance from the formation of a vacuum will result.

Inasmuch as I have illustrated no spring connecting the plunger and cylinder 2, there

would be no tendency, in the construction illustrated, for the door to close completely 35 after the arm 6 resumes its position against the wall 8. The spring of the usual spring-hinge, or some other extraneous spring, is therefore depended upon in the construction 40 illustrated to complete the closing movement of the door. Obviously, however, any desired arrangement of spring-device for forcing the door to the completely closed position may be employed in connection with my 45 invention.

The foregoing detailed description has been given for clearness of understanding only, and no undue limitation should be understood therefrom but the appended claim 50 should be construed as broadly as permissible in view of the prior art.

What I regard as new, and desire to secure by Letters Patent, is—

In a device of the character set forth, the combination of a bracket equipped with a pivot and stop, a link connected with said pivot and bearing against said stop, a spring connected with said bracket and tending to maintain said link in engagement with said stop, a cylinder, supporting means therefor, and a plunger movable in said cylinder and having jointed connection with said link. 55 60

ALBIN DANIELSON.
